(57) **CLAIM**

The ornamental design for an LED light module with cutouts, as shown and described.

DESCRIPTION

FIG. 1 is a perspective view of an LED light module showing a first embodiment of the new design;

FIG. 2 is a right side view thereof.

FIG. 3 is a left side view thereof.

FIG. 4 is a front view thereof.

FIG. 5 is a back view thereof.

FIG. 6 is a top view thereof.

FIG. 7 is a bottom view thereof.

FIG. 8 is a perspective view thereof showing the back plate removed for ease of illustration only;

FIG. 9 is a side view thereof showing the design mounted on a street post;

FIG. 10 is a perspective view of an LED light module showing a second embodiment of the new design; and,

FIG. 11 is a perspective view thereof showing the back plate removed for ease of illustration only.
